[57] CLAIM

The ornamental design for a combined furniture feet and apron, as shown and described.

DESCRIPTION

FIG. 1 is a front elevational view of a combined furniture feet and apron showing my new design, the rear being identical thereto;

FIG. 2 is a side elevational view;

FIG. 3 is an enlarged front elevational view of the right foot shown in FIG. 1;

FIG. 4 is a front elevational view of second embodiment of the combined furniture feet and apron shown in FIG. 1, the rear being identical thereto;

FIG. 5 is an enlarged front elevational view of the right foot shown in FIG. 4; and,

FIG. 6 is an enlarged side elevational view of FIG. 4.

The bottom of the combined furniture feet and apron forms no part of the claimed design. The broken lines shown throughout the views are for illustrative purposes only.
